UNITED STATES PATENT OFFICE.

HARRY F. SMOOTHERS AND EMANUEL E. NORQUIST, OF KANSAS CITY, MISSOURI.

APPARATUS FOR SUPPLYING GASOLINE AND COMPRESSED AIR.

1,266,337.

Specification of Letters Patent. Patented May 14, 1918.

Application filed April 24, 1916. Serial No. 93,194.

To all whom it may concern:

Be it known that we, HARRY F. SMOOTHERS and EMANUEL E. NORQUIST, citizens of the United States, residing at Kansas City, in the county of Jackson and State of Missouri, have invented certain new and useful Improvements in Apparatus for Supplying Gasoline and Compressed Air, of which the following is a specification.

10 This invention relates to apparatus for supplying air under pressure or for utilizing air to supply gasoline from a tank protected from fire.

To this end the invention consists in certain novel and peculiar features of construction and combinations of parts as hereinafter described and claimed; and in order that it may be fully understood reference is to be had to the accompanying drawing 20 which represents an elevational view of the apparatus.

Figure 1, is an elevation of apparatus embodying the invention.

Fig. 2, is a fragmentary view showing the connection between the tire inflating device and the main air pipe of the apparatus.

Referring to the drawing in detail, 1 represents an air compressor of any suitable type, driven by a belt 2 or the like running 30 from a gasoline engine or other motive power, not shown.

Leading from the compressor is a discharge pipe 3 controlled by a hand operated valve 4 and equipped with a relief or 35 safety valve 5 of any conventional type; and between said valves 4 and 5 a short pipe 6 connects pipe 3 with a tank 7 for containing air under high pressure, say two-hundred pounds. The tank is protected by a gage 40 8 to indicate the pressure developed, and is equipped with a discharge pipe 9 controlled by hand operated valve 10. The discharge pipe 9 extends below and upward into a hollow post or casing 11, and a door-controlled box 12 mounted on the post or casing, the door 13 being adapted to be locked in closed position to prevent unauthorized access to the interior of the box.

Within the box the pipe 9 is equipped with 50 a valve 14, an air pressure reducing valve 15, an air gage 16 and a relief or safety valve 17, and from the latter the pipe extends downward through the box and post and connects with a gage pipe 18 extending 55 from a point above the ground to and com-

municating with a gasoline supply tank 19 buried at a safe distance under ground. The upper end of the pipe 18 is closed by a removable cap 20, and said cap also engages the upwardly projecting stem 21 of a float 60 22 in the gasoline tank. When the cap is removed the gasoline causes the float to rise and project its stem out of the upper end of said pipe and thus indicate the depth of the gasoline in the tank, it being understood 65 that the stem is of such length that it will not project from said pipe when the supply of gasoline is exhausted.

The tank is provided with a filling tube 23 which also projects above the ground and 70 is normally closed by a removable cap 24. A gasoline discharge pipe 25 extends down into the tank and terminates near the bottom of the same in a strainer 26 to prevent foreign substances being forced out of the 75 tank with the gasoline, and said pipe extends up through the hollow post or casing to a gasoline meter 27 located in the box. From said meter leads a discharge pipe 28 equipped within the box with a filter 29, 80 and connected to the discharge end of pipe 28 is a hose 30 having a flanged nozzle 31. When the hose is not in service the nozzle is arranged within the box by slipping it in a notch 32 in the bottom thereof so that the 85 flange of the nozzle shall rest on said bottom. When the door 13 is closed and locked in any suitable manner not shown, the nozzle cannot be withdrawn from the box, but when the door is open said nozzle can be 90 readily slipped out of said notch. By thus securing the nozzle in the box precaution is had against unauthorized use of the device, but to more securely guard against withdrawal of gasoline from the tank by an unauthorized person the pipe 25 at a point underground is provided with a valve 33, and the stem 34 of said valve extends up through the post and into the box and terminates in a handle 35 for convenience in opening and closing said valve 33.

Tapped off from the air pipe 9 within the hollow base is a branch pipe 36 equipped with an ordinary pressure regulator valve 37, air gage 38 and air hose connection 39. 105 Proper adjustment of the valve 37 determines the pressure at which air may pass through the hose connection 39, the gage 38 indicating such pressure. The valve 37 of course may be manipulated to entirely shut 110

off the supply of air to gage 38 and to hose connection 39. When it is desired to charge a tire with air, a suitable hose, not shown, is fitted to the connection 39. The hose will 5 be equipped at its tire engaging end, with the customary automatic chuck or valve, which opens when fitted to the tire stem and closes when disengaged therefrom. To give access to the connection 39 and the 10 valve 37, and to expose the gage 38 to view, the post is provided with an opening 40, and a door 41 to close said opening, any suitable fastening devices for the door being employed.

15 Assuming that the tank 7 is charged with air under suitable pressure, say two-hundred pounds, and that the tank 19 stands charged with gasoline, an authorized person desiring to supply a motorist with ten gallons of 20 gasoline will open the door 13, withdraw the nozzle 31 and direct it properly with respect to the tank to be filled and open valve 33. As this is done, the air from tank 7 passes through pipe 9 and enters the tank 25 19 at a reduced pressure due to passage through the pressure reducing valve 15, as it is not necessary or desirable to turn the full pressure of air from tank 7 into the gasoline tank. The pressure of the air entering the gasoline tank is indicated by gage 30 16 and can be varied of course by adjustment of the reducing valve. The pressure of the air on the charge of gasoline forces the latter through the strainer 26 and up 35 through pipe 25 and gasoline meter 27 which indicates the quantity of gasoline passing therethrough, and then through pipe 28 where it is filtered by filter 29, and thence through the hose pipe 30 to the tank of the 40 automobile. When the car tank receives the proper amount of gasoline the valve 33 is closed by manipulation of the handle 35, after which the nozzle is returned to its position in the box, the door 13 is reclosed and 45 locked. It will thus be seen that a supply of gasoline can be vended quickly and easily without any labor of pumping or the like, and that when the valve 33 is closed the destruction by fire of the building containing 50 the apparatus will not result in an explosion of the gasoline in tank 19 due to the fact that the same is protected by embed- 55 ment under the floor of the garage or other service point.

55 In the event that the pressure reducing valve 15 gets out of order from any cause no air under a destructively high pressure can enter the gasoline tank because the relief or safety valve 17 will permit said air 60 to escape.

If a motorist desires to inflate his tires at say sixty pounds pressure, a properly authorized person can open the door 41 and establish communication by a hose as suggested, between connection 39 and the stem

of the tire to be inflated, and then adjust the valve 37 to permit the air to flow through pipe 36, and the connections mentioned to the tire and also to the gage 38, and as soon as the latter indicates a pressure of 60 70 pounds the valve 37, is adjusted to cut off the supply of air through said branch pipe 36. The hose connection is then broken and the door 41 reclosed and locked if desired.

We claim:

1. The combination with a compressed air tank and means for supplying the same with air under pressure, of a casing above and a gasoline tank below ground, a pipe leading from the air tank through the casing to 20 the gasoline tank, a pipe running from the gasoline tank through the casing and terminating outside the same, a meter on said last-named pipe within the casing, a valve on said pipe, means within the casing for 25 operating said valve, a hose for receiving gasoline from the pipe leading from the gasoline tank, and provided with a nozzle normally projecting into the casing, and a door normally controlling access to the casing and said valve operating means and when closed also preventing the removal of 30 the nozzle from the casing. 90

2. The combination with a compressed air tank and means for supplying the same with 95 air under pressure, of a casing above and a gasoline tank below ground, a pipe leading from the air tank through the casing to the gasoline tank, a pipe running from the gasoline tank to the casing and terminating outside the same, a meter and a filter on said last-named pipe within the casing, a valve on the same pipe below ground, means within the casing for operating the valve, a hose for receiving gasoline from the pipe leading 100 from the gasoline tank, and provided with a nozzle normally projecting into the casing, and a door normally controlling access to the casing and said valve operating means and when closed also preventing the removal 110 of the nozzle from the casing. 110

3. The combination with a compressed air tank and means for supplying the same with air under pressure, of a casing above and a gasoline tank below ground, a pipe leading 115 from the air tank through the casing to the gasoline tank, a valve on said pipe within the casing, a reducing valve, an air gage and a relief valve on said pipe within the casing between the first-named valve and the gasoline tank, a pipe running from the gasoline tank to the casing and terminating outside the same, a meter and a filter on said last-named pipe within the casing, a valve on the same pipe below ground, means within the casing for operating the valve, a hose for receiving gasoline from the pipe leading from the gasoline tank, and provided with a nozzle normally projecting into the casing, and a door normally controlling access to 120 125 130

the casing and said valve operating means and when closed also preventing the removal of the nozzle from the casing.

4. The combination with a compressed air tank and means for supplying the same with air under pressure, of a casing above and a gasoline tank below ground, a filling tube extending from the gasoline tank to a point above the ground, a float gage accessible from 10 a point above ground, to indicate the quantity of gasoline in the tank, a pipe leading from the air tank through the casing to the gasoline tank, a valve on said pipe within the casing, a reducing valve, an air gage and 15 a relief valve on said pipe within the casing between the first-named valve and the gasoline tank, a pipe running from the gasoline tank to the casing and terminating outside the same, a meter and a filter on said last-named pipe 20 within the casing, a valve on the same pipe below the ground, means within the casing for operating the valve, a hose for receiving gasoline from the pipe leading from the gasoline tank, and provided with a nozzle 25 normally projecting into the casing, and a door normally controlling access to the casing and said valve operating means and when closed also preventing the removal of the nozzle from the casing.

- 30 5. The combination with a compressed air tank and means for supplying the same with air under pressure, of a casing having a door

controlled opening, a valve controlled pipe leading from the compressed air tank into the casing, a branch pipe leading from the 35 first-named pipe within the casing and accessible when said door is open, a tire pressure regulating valve, an air gage and hose connection on said branch pipe, a door controlled box upon the casing through which 40 said first-named pipe extends beyond the said branch pipe, a gasoline tank under-ground connected to the discharge end of the pipe extending through the box, a pressure reducing valve, an air gage and a relief valve on 45 said pipe within the box, an under-ground valve on said pipe, a rod for operating said valve extending up through the casing into the box and provided with an operating handle in the latter, a gasoline discharge 50 pipe leading from the lower part of the gasoline tank up through said casing and box to a point outside the latter, a meter and a filter on said gasoline discharge pipe within the box, and a hose connected to the outside end 55 of said gasoline discharge pipe and provided with a nozzle for projecting into the box and prevented from withdrawal therefrom when the door thereof is closed.

In testimony whereof, we affix our signatures.

HARRY F. SMOTHERS.
EMANUEL E. NORQUIST.
